PAPER BAG

Morris Katz, Bronx, N. Y.; Sophie Katz ad-
ministratrix of said Morris Katz, deceased

Application October 30, 1943, Serial No. 508,344

5 Claims. (Cl. 229—54)

This invention relates to conventional paper bags, such as used by storekeepers, particularly the grocer for placing articles of merchandise for convenient handling by the purchaser. More particularly, the invention relates to means for forming a reinforced handle structure for bags of this kind, as well as in the method of constructing and applying handle members to opposed sides of the bag. The novel features of the invention will be best understood from the following description when taken together with the accompanying drawing, in which certain embodiments of the invention are disclosed, and in which the separate parts are designated by suitable reference characters in each of the views, and in which:

Fig. 1 is a perspective diagrammatic view of a paper bag, showing one form of handle construction which I employ.

Fig. 2 is an enlarged section on the line 2—2 of Fig. 1, illustrating the handle in operative position.

Fig. 3 is a view similar to Fig. 2, showing a modified adaptation of the invention.

Fig. 4 is a perspective exploded view illustrating the manner of assembling the handle members with upper edge portions of a paper bag.

Fig. 5 is a view similar to Fig. 4, showing another adaptation of the invention.

Fig. 6 is a plan view of a blank on which handle members shown in Figs. 1, 2 and 4 are formed; and

Fig. 7 is a view similar to Fig. 6 of the blank, employed in forming handle members as illustrated in Figs. 3 and 5.

In the construction of paper bags, such as used by grocers, bakers, dealers in vegetables, and other establishments, these bags have been left plain, and used as a wraper for a single article, or as a means for holding a number of articles together in a single package, and unless tied with a string or cord, such bags when filled have necessitated carrying in the arms.

It is the purpose of my invention to apply to paper bags of the kind under consideration, in a simple and practical manner, reinforcing members which form in conjunction with cutout side walls of the paper bag handle members by means of which a bag of the kind under consideration may be conveniently carried in the hand. In addition to providing a handle for bags of the kind under consideration, these members also serve to support the upper open end of the bag in a closed or partially closed position retaining

articles against displacement from the open end of the bag.

While the invention is herein described as applied specifically to the conventional paper bag, it will be apparent that the same is also applicable for use in connection with what is known as shopping bags, composed of heavier and stronger materials, and which would dispense with the use of conventional cord handle now used on such shopping bags.

In Figs. 1, 2, 4 and 6, is shown one adaptation of the invention, in which the paper bag is generally indicated at 10, and in practise, upper opposed side walls 11, 12 of the bag have semi-circular die cuts 13 to form flaps 14, 15 respectively.

At 16 in Figs. 4 and 6 is shown a blank from which independent handle members 17 and 18 are to be formed. The blank comprises a rectangular sheet of thick paper or light cardboard die cut centrally and transversely, as seen at 19, to form weakened end wall portions, as at 20, which can be freely ruptured in severing the handle members 17 and 18. The handle member 18 has a semi-circular die cut 21, which forms a flap 22 foldable along the line 23.

The handle member 17 has a crescent shape opening 24, cut from the material thereof, and substantially similar in form to the opening formed in the handle member 18, when the flap 22 is in folded position. These registering openings are adapted to receive the fingers of a hand when carrying a bag. The handle members include outwardly and downwardly turned flanges 25 at their upper edges which are disposed upon and secured to the outer surfaces of the opposed walls 11 and 12 of the bag. The remainder of the body portion of the members 17 and 18 being disposed upon the inner surfaces of these walls, as will clearly appear from a consideration of Fig. 2 of the drawing.

In securing the handle members in position, the die cut and scored blank 16, as seen in Fig. 6 of the drawing is coated on one surface with a suitable adhesive, and then folded centrally to have the flaps 25 stand outwardly and laterally in the manner seen in Fig. 4, and when so positioned, the blank is placed between opposed walls 11, 12 of a bag, bringing the cutouts 21, 24 in registering alignment with the die cuts 13, after which the walls 11 and 12 are placed onto the outer exposed surfaces of the handle members 17 and 18. The flanges 25 are then moved into firm engagement with outer surfaces of the walls 11 and 12.

After the parts have been securely adhered together, the walls 11 and 12 are spread apart by rupturing the blank 16 at the points 20, thus leaving one handle member 17, 18 on each of the opposed walls 11, 12. In constructing the blank 16, the blank is also scored centrally and longitudinally to form a fold line 26, so that in the event of excessive filling of the bag with merchandise, said walls 11 and 12 will fold centrally and longitudinally of the handle members, thus eliminating any strain upon the side walls of the bag adjacent the ends of said handle members.

Bearing in mind that the entire bag construction is for a give away bag, added expense in the cost of producing the bag is minimized. It will be understood where expense is not a factor, the upper edge portion of the side walls 11 and 12 of the bag may be reinforced in a number of different ways to give added strength to the entire bag structure.

In the use of the bag, it will be apparent that the tongue or flap 22, with the paper flap 15 secured thereto will be free to pass through the opening 24 and the handle member 17, and folded into the position indicated in Fig. 2 in carrying the bag in the hand. In such uses, the flap 14 may be folded inwardly in the manner shown in said figure.

In the construction shown in Fig. 2, the surfaces of the handle members 17 and 18 are brought into close proximity into each other, resulting in a corresponding relationship of the side walls 11 and 12 of the bag. However, in Fig. 3 is shown a slight modification, wherein a relatively thick handle is provided by flaps which retain the walls in spaced relationship to each other. While this member is applicable to handle members constructed from blanks of the general contour shown in Fig. 6, I have shown this feature of the invention as applied to modified form of blanks, illustrated at 27 in Fig. 7 of the drawing, and it is shown in a folded position in Fig. 5.

The blank of Fig. 7 differs in three primary respects, first in that the flange portions 28 are arranged adjacent each other on the blank and separated by the die cut 29, having the weakened ends 30 similar to the weakened ends 20, and that the die cuts 31 in the handle member 32 are of different shape, to form more or less oblong flaps 33 on both handle members, and further, that both of the flaps 33 have score lines 34, which form narrow flange edges 35.

With this arrangement of the parts on the blank, the blank is folded into the M formation shown in Fig. 5 in assemblage of the blank with side walls 36 and 37 of a paper bag so that the two flanges 28 fit between the walls, and will be disposed on inner surfaces of the walls, whereas the handle members 32 will be disposed on outer surfaces of the walls. In other words, a reverse of the arrangement shown in Fig. 4.

With this construction, the side walls 36 and 37 of the bag will have cutout apertures 38, which will register with the flaps 33, including the flange portions 35 thereof.

The elongated contour of the cutouts in forming the flaps 33 will produce wider finger receiving openings in the bag, and the foldable flanges 35 also operate to support the opposed walls 36, 37 of the bag in spaced relationship to each other in the manner illustrated in Fig. 3 of the drawing. This forms, of the overlapping flaps 33, a thickened handle portion which will eliminate

the cutting action on the fingers of the hand in carrying a heavily loaded bag, as might be the case with a structure as seen in Fig. 2 of the drawing. The blank 27 is also scored centrally and longitudinally to form a fold line 39, similar to the fold line 26, which would become effective only as and when the bag walls 36, 37 are spread apart beyond the limits of the flanges 35.

It will be understood that the blanks shown in Figs. 6 and 7, which are foldable in the manner illustrated in Figs. 4 and 5 still adapt them for automatic formation and assemblage in paper bags, thus minimizing the cost of producing handled bags of the kind under consideration, and further will dispense with as much hand labor as possible in the production of the bags.

In the modification illustrated in Figs. 3, 5 and 7 of the drawing, the tongues have been omitted from the opposed walls of the bag in forming the openings 38 simply to illustrate another adaptation of the invention. It will be apparent, however, that the tongues similar to the tongues 14 and 15 may be attached to the flaps 33. In like manner, it will be apparent that the flaps or tongues 14, 15 of the structure shown in Figs. 1, 2 and 3 may be omitted.

Having fully described my invention, what I claim as new and desire to secure by Letters Patent is:

30. The method of forming reinforced handles for the upper open end portions of paper bags, which comprises forming finger receiving apertures on opposed walls of the bag adjacent the open end thereof, die forming and scoring a duplex handle blank to form finger receiving apertures on wide portions of the blank, folding the blanks centrally to dispose the finger apertures of the wide portions thereof in position for registration with each other, then mounting the folded unit upon opposed walls of the bag with the apertures of said wide portions in registering alignment with the apertures of the bag, securing the unit to said opposed walls, and then severing the unit centrally to form on each of the opposed walls of the bag an independent handle portion.

35. The method of forming reinforced handles for the upper open end portions of paper bags, which comprises forming finger receiving apertures on opposed walls of the bag adjacent the open end thereof, die forming and scoring a duplex handle blank to form finger receiving apertures on wide portions of the blank, folding the blanks centrally to dispose the finger apertures of the wide portions thereof in position for registration with each other, then mounting the folded unit upon opposed walls of the bag with the apertures of said wide portions in registering alignment with the apertures of the bag, securing the unit to said opposed walls, and then severing the unit centrally to form on each of the opposed walls of the bag an independent handle portion.

40. The method of forming reinforced handles for the upper open end portions of paper bags, which comprises forming finger receiving apertures on opposed walls of the bag adjacent the open end thereof, die forming and scoring a duplex handle blank to form finger receiving apertures on wide portions of the blank, folding the blanks centrally to dispose the finger apertures of the wide portions thereof in position for registration with each other, then mounting the folded unit upon opposed walls of the bag with the apertures of said wide portions in registering alignment with the apertures of the bag, securing the unit to said opposed walls, and then severing the unit centrally to form on each of the opposed walls of the bag an independent handle portion, and including on said duplex blank foldable flange portions arranged upon and secured to surfaces of said walls of the bag opposed to that upon which the wide apertured portions are secured.

45. A device for forming dual handles for paper bags, said device comprising a blank having a long central cut to divide the blank into similar side portions joined by two short uncut weakened rupturable parts at side edges of said blank and ends of said cut, each side portion comprising a wide part and a narrow part foldable one with respect to the other, and each wide part having a cutout to form a finger receiving aperture and to form of each wide part a handle member.

4. A device for forming dual handles for paper bags, said device comprising a blank having a long central cut to divide the blank into similar side portions joined by two short uncut weakened rupturable parts at side edges of said blank and ends of said cut, each side portion comprising a wide part and a narrow part foldable one with respect to the other, each wide part having a cut-out to form a finger receiving aperture and to form of each wide part a handle member, and the rupturable parts hingedly joining said wide parts.

5. A device for forming dual handles for paper

bags, said device comprising a blank having a long central cut to divide the blank into similar side portions joined by two short uncut weakened rupturable parts at side edges of said blank and ends of said cut, each side portion comprising a wide part and a narrow part foldable one with respect to the other, each wide part having a cut-out to form a finger receiving aperture and to form of each wide part a handle member, and the rupturable parts hingedly joining said narrow parts.

MORRIS KATZ.
